(57) **CLAIM**

The ornamental design for a multiport for making optical connections, as shown and described.

DESCRIPTION

FIG. 1 is a top perspective view of a multiport for making optical connections;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

In FIGS. 1-7, the outermost broken lines immediately adjacent to the full line showing the claimed design represent the bounds of the claimed design while all other broken lines are directed to environment and are for illustrative purposes only; the broken lines form no part of the claimed design. In addition, in FIGS. 1 and 2, the unshaded surfaces between the solid line circles and broken line circles form no part of the claimed design.
